MONTGOMERY KNIGHT, OF HOLYOKE, MASSACHUSETTS, ASSIGNOR TO WESTINGHOUSE ELECTRIC & MANUFACTURING COMPANY, A CORPORATION OF PENNSYLVANIA.

COMPENSATING DEVICE.

Application filed October 3, 1925. Serial No. 60,291.

My invention relates to compensating means for electroresponsive devices, and particularly to means for compensating electric meters or flux-producing elements for 5 the effects of varying conditions, such as temperature changes, thereon.

One object of my invention is to provide a compensating device, of the above-indicated character, that shall be simple and 10 durable in construction, economical to manufacture and effective in its operation.

Another object of my invention is to provide a compensating device that shall be readily adapted for co-operation with a 15 standard structure without material change in the latter.

Another object of my invention is to provide a temperature compensating device that shall retain its characteristics as initially calibrated.

Another object of my invention is to provide a flux-producing compensating device for co-operation with flux-producing elements, in contradistinction to the many 25 forms of devices which only modify the fluxes to be compensated but do not produce fluxes.

A further object of my invention is to provide a temperature-responsive compensating 30 device that shall comprise differentially-related elements of such temperature coefficients that the element with which they are co-operating under given conditions is unaffected but that shall compensate the flux 35 of the element in accordance with variations from said conditions.

With such objects in view, as well as other advantages which may be incident to the utilization of the improvement, the 40 invention consists in the parts and combinations thereof hereinafter set forth and claimed, with the understanding that the several necessary elements constituting the same may be varied in proportion and arrangement without departing from the 45 nature and scope of the invention.

In the prior art, watthour meters and other devices employing electromagnetic fluxes as essential elements of their operation 50 have been subject to serious errors caused by temperature changes and other variable conditions.

Many suggestions for the correction of such errors have been made most of which 55 are impracticable for various reasons, one

being that certain of the suggestions require radical and expensive changes in the devices with which they are adapted to co-operate.

One suggestion, which has been advanced in a wide variety of forms, calls for the use of a movable keeper for the meter magnets to be moved by a temperature-responsive bimetallic element. Such device is usually relatively cumbersome and only adaptable for its purpose with the exercise of extreme care and skill. This is because of the size of the bimetallic element required to obtain sufficient movement of the keeper and the usually limited space for such a device in meters of standard practice.

Other suggestions have been made which are not subject to the above-mentioned objection, but all of them, to the best of my knowledge, only modify the flux they are to compensate and do not produce a variable flux to positively aid or oppose the compensated flux as by my invention.

A further objection to certain of the prior art devices is that they do not sufficiently retain their original characteristics, as in the fatigue of the bimetallic elements.

It is my aim to provide means for compensating for variable conditions in a flux-responsive device by positively aiding and opposing the operating flux, in contradistinction to merely modifying it, and to provide a device that shall not only retain its initially-calibrated characteristics but that may be added to a standard structure without material change therein.

Accordingly, in practicing my invention, I provide co-operating flux-producing elements that are so differentially related to each other and to the device to be compensated and that are constructed to be of such different characteristics as not to affect the device under given conditions, but that shall positively aid or oppose the flux of the device in accordance with the extent and direction of variation from said conditions.

Figure 1 of the accompanying drawings is a diagrammatic view of a device embodying my invention;

Fig. 2 is a diagram of the device of my invention, as applied to a watthour meter;

Fig. 3 is a diagram, in simplified form of the device of Fig. 2, with certain parts omitted; and

Fig. 4 is a view similar to Fig. 3 of a modified form of my invention.

In one of its simplified forms, as shown in Fig. 1, the device comprises a main flux-producing winding 1, such as one of the operating windings of a watthour meter. 5 In this instance, the winding 1 represents the series winding or windings of a watthour meter of usual type.

Connected in series relation to the winding 1 are a pair of parallel-connected coils 10 2 and 3 of materials, such as copper and advance, respectively, that are differentially wound and otherwise so constructed and related to each other as to produce equal and opposite fluxes under given temperature conditions. 15

The fluxes of the coils 2 and 3 are so related to the main operating flux of the winding 1 that, at said given temperature, they have no effect thereon but that, with a rise or fall 20 of temperature, they become unbalanced to produce a resultant flux. This resultant flux may be adapted to either aid or oppose the flux to be compensated in one direction from said given temperature and to respectively 25 oppose or aid the flux in the opposite direction as desired.

The adaptation of the above-described suggestion to a watthour meter of standard form is illustrated more clearly in Fig. 2, 30 in which a laminated core structure 5, a shunt or voltage winding 6, a series winding or windings 8—9, corresponding to the winding 1 of Fig. 1, and a lag plate 10 are constructed and related in a usual manner but 35 augmented by coils 11—14 and 12—15, corresponding to the coils 2 and 3 of Fig. 1.

The core structure 5 is of a usual form comprising a main central leg or pole portion 16 around which the voltage coil 6 is 40 disposed and which is divided at its outer or lower end into two smaller portions 17. These portions are paired with similar portions 18 projecting from the sides 19 of the core structure 5 and one of these pairs, comprising one of the portions 17 and one of the 45 portions 18, is surrounded by the coils 8, 11 and 12, while the other is surrounded by the coils 9, 14 and 15.

A disc armature 21, mounted on a shaft 22, 50 is disposed in an air gap 23 between the pole portions 17—18, at one side thereof, and a bottom or cross portion 24 of the magnet structure 5, at the other side, and is adapted for actuating an indicating member or meter register (not shown) in a usual and well-known manner.

Referring to Fig. 3, which is a simplified showing of the device of Fig. 2, with the core structure 5, the voltage coil, the lag plate 10, the shaft 22 and the disc 21 omitted, the coils 8, 9, 11, 12, 14 and 15 are related to each other in the manner shown, with the direction of the flux of each thereof indicated by an arrow therein. An ordinary watthour meter, as shown in Fig. 3, comprises the series

coils 8 and 9, with the fluxes thereof in opposite directions, as indicated by the arrows so that, when augmented by the flux from the voltage coil, quadrature-related fluxes for the rotation of the disc 21 are produced. 70 Added to this structure, in accordance with my invention, the coils 11, 12, 14 and 15 are so constructed and related to each other and to the coils 8, 9 and 6 as not to affect the operation of the meter at a given temperature. 75 However, by reason of the higher temperature coefficients of the coils 11 and 14 relative to the temperature coefficients of the coils 12 and 15, when a rise or fall of temperature occurs, an unbalanced or resultant flux will be produced, as in the form of device shown in Fig. 1, to augment or oppose the ordinary fluxes of the meter in one direction from the given temperature and to oppositely affect the meter fluxes in the opposite direction. 80 85

This action will be apparent from a study of the arrows in Fig. 3, in which the fluxes of the coils 11 and 12 normally cancel or nullify each other as do the fluxes of the 90 coils 14 and 15, thus leaving, at said given or predetermined temperature, only the effect of the fluxes in the coils 8 and 9 as modified by the flux produced by the voltage coil 6. 95

The fluxes from the coils 8, 9 and 6 are ordinarily affected by temperature changes to cause the meter to operate inaccurately. However, in the device of my invention, this change is opposed substantially in accordance with its extent by the coils 11, 12, 14 and 15 to cause the meter to operate more accurately over a relatively wide range of temperature change. 100

By properly proportioning the compensating coils and the lag plate 10 both as to relative magnitude and temperature coefficients, complete compensation for temperature changes of all power factors may be effected. 105

Thus by the simple expedient set forth, a standard watthour meter or other device may be quickly and economically compensated for errors incident to temperature changes without materially altering its construction. 110 115

In the modification of my invention shown in Fig. 4, in which corresponding parts are designated by corresponding reference characters, the construction and operation are similar except that a variable reactor 26 is substituted for the lag plate 10 in the branch of the parallel compensating circuit in which the low-temperature-coefficient coils 12 and 15 are disposed. 120 125

In this construction, in which temperature compensation is also effected for inductive leads at all power factors, the lagging, instead of being effected by the lag plate 10, as in the form of my invention shown in 130

Figs. 2 and 3, is effected by the reactor 26 in the low-temperature-coefficient circuit.

In accordance with the provisions of the patent statutes, I have described the principle of operation of my invention, together with the apparatus which I now consider to represent the best embodiment thereof; but I desire to have it understood that the apparatus shown and described is only illustrative and that the invention may be carried out by other means.

I claim as my invention:

1. The combination with a flux-producing winding, of a pair of coils connected in parallel to each other, the parallel circuit formed by the coils being connected in series relation to said winding and adapted at a given temperature to produce equal and opposite fluxes, said coils being constructed of materials having different temperature coefficients and the fluxes thereof being related to the flux of the winding to compensate the same for temperature variations from said given temperature.

2. The combination with a pair of oppositely-wound, series related, flux-producing windings, of a parallel circuit connected in series with said windings comprising two branches each including a coil disposed coaxially with one of said windings, said parallel circuit being normally inoperative to produce flux under a given temperature condition, but effective to aid or oppose the fluxes of said windings in accordance with variations from said condition.

3. The combination with a pair of oppositely-wound, series-related, flux-producing windings, of a parallel circuit connected in

series with said windings, comprising a plurality of branches, each of said branches 40 including a plurality of oppositely wound coils, said branches comprising different temperature coefficients, a certain coil of each of said branches being disposed coaxially with one of said windings.

4. In an induction meter, the combination with a magnetizable core member and actuating windings thereon, of means for compensating the meter for temperature variations comprising coils connected in differential parallel relation, said coils being adapted for normally producing equal and opposite fluxes under given temperature conditions but having different temperature coefficients and related to the windings to aid 55 or oppose the winding fluxes in accordance with variations from said given temperature conditions.

5. In an alternating-current instrument, the combination with means for producing 60 actuating and controlling fluxes, of means comprising flux-producing structure for causing a predetermined phase displacement between the actuating fluxes of the meter at a given power factor and for producing 65 normally equal and opposite fluxes at a given temperature which become unbalanced to produce flux to compensate said first flux-producing means for a change in flux magnitude and phase displacement caused by 70 temperature change.

In testimony whereof, I have hereunto subscribed my name this 30th day of September, 1925.

MONTGOMERY KNIGHT.
